UNITED STATES PATENT OFFICE.

ALFRED G. F. KUROWSKI, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed May 15, 1925. Serial No. 30,472.

This invention relates to a typewriting machine combined with a sound-deadening casing. One of its features relates to means whereby the platen may be rotated from the outside of the casing. The Underwood standard typewriter, in connection with which this invention is illustrated, comprises key-controlled mechanism for shifting the platen to either upper or lower case type positions. There is provided an exterior finger-wheel mounted on a bracket, the latter being movable by the action of the shift-key to maintain operative relationship between the finger-wheel and the platen-axle. The finger-wheel is fast to a shaft that telescopes into and is splined to a tube which serves as the platen-axle. The carriage may travel while the finger-wheel is stationary outside of the casing.

The cover of the casing is mounted on rear hinges. Since the finger-wheel is placed above the body-part of the casing and extends through the side wall of the hinged cover, it is necessary to provide a slot in the side of the cover to clear the shaft of the finger-wheel. Said slot may be sealed with felt.

Another feature relates to means for controlling the trailing edge of the work-sheet, especially when it is a stiff card or heavy paper. It is an aim to prevent the edge of the sheet from dragging against the sides of the casing. Such drag is apt to have a retarding action on the carriage. A plate at the introductory side of the platen is fast to the regular rear table of the machine. Said plate extends downwardly and rearwardly forming a pocket in which the trailing edge of the card is guided, the card or sheet forming a loop previous to passing around the platen.

Other features and advantages will hereinafter appear.

In the accompanying drawings,

Figure 1 is a side view in elevation of a sound-deadening casing adapted to an Underwood standard typewriting machine, showing the machine enclosed therein.

Figure 2 is a plan view of the carriage of an Underwood standard typewriting machine, showing a work-sheet-supporting plate attached thereto.

Figure 3 is a cross-sectional view in elevation of the casing and the machine, showing the means for supporting a finger-wheel

outside of the casing, said means being attached to the platen-shifting mechanism of the machine.

Figure 4 is a cross-sectional view through the center of the platen.

Figure 5 is a cross-sectional view through the line 5—5 of Figure 4.

The Underwood standard typewriting machine is operated in the usual manner from the outside of a casing having a front opening through which the keyboard extension 10 of the machine protrudes. Within the keyboard extension there are positioned banks of keys 11, which operate type-bars 12 to strike a platen 13 revolubly mounted 70 on a platen-frame 14 borne by a carriage 15 arranged for travel upon rails 16 and 17 fixed to the frame 18 of the machine.

In the Underwood machine, there is provided mechanism to shift the platen for 75 either upper or lower case types 19. Said mechanism comprises a key 20 rocking a lever 21 on a shaft 22 against the tension of a spring 23. The lever 21 is provided with an upwardly-extending arm 24 engaging 80 with plates 25 mounted on a cross-shaft 26 fast thereto. Upon said plates there is mounted a cross-bar 27 operatively connected to the platen-frame by means of a roller 28 rotatably mounted on said frame.

The casing, in connection with which this invention is illustrated, comprises a body-part 29 and a cover 30 rockably mounted on the casing by means of hinges 31. The body-part comprises front, side and rear walls, 90 respectively, indicated by the numerals 32, 33 and 34, the walls forming an integral part of a supporting base-plate 35 upon which the feet 36 of the machine rest. The cover comprises side walls 37 forming an integral part 95 of an arcuate top 38, which terminates at the rear thereof with a straight vertical wall 39. Both the body-part and the cover are provided with layers of sound-deadening material, indicated generally by the numeral 40 for the purpose of further deadening the sounds arising from the operation of the machine.

In order that the platen may be rotated from the outside of the casing without necessitating the displacement of the cover, there is provided a finger-wheel 41 adjacent the side wall of the casing. Said finger-wheel is operatively connected to the platen by means of a shaft 42 fast to the finger-

wheel 41. Said shaft is collapsibly mounted in a hollow shaft or tube 43 which serves as the platen-axle. The platen-axle or tube 43 is journaled in platen side frames 44 and 5 is provided at the ends thereof with finger-wheels 45, one of which is provided with a set-screw 46 and the other of which is secured to the tube by means of a shaft 47 driven therein. The platen is mounted on 10 the axle in the regular manner by means of end pieces 48 secured to the axle by means of screws 49, one of which is made longer to screw through the tube and to press upon the shaft 47.

15 The shaft 42 is provided with a splined groove 50 engaging with the end of a screw 51 secured to one of the finger-wheels 45. The purpose of this groove and screw is to 20 rotatably connect the platen to the finger-wheel 41 outside of the casing, while at the same time rendering the carriage operable for letter-space travel. For the purpose of preventing lateral displacement of the shaft 42 when the carriage is operated, there is 25 provided a collar 52 secured to the shaft by means of a screw 53.

In order that, when the platen is shifted to upper-case position, the position of the finger-wheel 41 will be maintained substantially 30 in line with the axis of the platen, to thus eliminate any binding of the shaft 42 against the wall of the tube 43, there is provided mechanism operatively connected to the carriage-shifting key 20 in a manner to 35 effect the raising of the finger-wheel simultaneously with the shifting of the platen. Said mechanism comprises a rigid bracket 54 fast to one of the plates 25 of the platen-shifting mechanism by means of screws 55.

40 The bracket 54 extends outwardly from the machine frame and terminates with a bent-up tab 56 having a stud 57 fast thereto upon which a roller 58 is rotatably mounted. The roller 58 engages with a cam face 59 of a 45 piece 60 pivotally mounted on a stud 61 fast to a bracket 62 forming a part of the body-part to which it is secured by means of screws 63. The bracket 62 is provided with a slot 64 to permit the up-and-down travel 50 of the shaft 42 when urged by the action of the roller 58 actuating upon the cam face 59. It will be noted that the cam face 59, slot 64 and piece 60 may be designed so that the travel of the finger-wheel will correspond to 55 the travel of the platen. It will also be noted that the bracket 62 is secured to the body-part of the casing in front of a slot 65 in the cover, to thus seal the opening and prevent the emission of sound therethrough.

60 Another feature of this invention relates to means for facilitating the handling of stiff work-sheets within sound-deadening casings. In practice it has been found objectionable to have cards and other stiff work-sheets extend outwardly from the platen, 65

because the bottom edge of a card tends to both damage the lining of the casing and retard the travel of the carriage. In this invention, there is provided a plate 66 at the rear of the platen, which plate extends substantially the full width of the platen and 70 is fastened to the rear table 67 by means of screws 68. Said plate 66 extends upwardly conforming to the outline of the table 67, and extends downwardly and rearwardly at 75 69 forming the inner wall of a pocket 70 for receiving the trailing edge 71 of a work-sheet 72. At its rearmost end the plate is again bent upwardly at 73 forming a rear wall 74 for said pocket 70, which wall terminates with an outwardly-extending bend 75 to facilitate the insertion of the bottom edge of the work-sheet or card into the pocket, as shown in Figure 1, in which the card forms a loop 76 at the top thereof. 80

Variations may be resorted to within the scope of the invention, and portions of the improvements may be used without others. Having thus described my invention, I claim:

1. The combination with a typewriting machine including an upwardly-shiftable platen and a hollow platen-axle, of a sound-deadening casing including a lower body-part and a slotted cover hinged thereto, and means for rotating the platen from outside the casing, said means including a splined shaft telescoping into said platen-axle and arranged to extend therefrom through an uprightly-disposed slot in the end wall of 95 said cover.

2. The combination with a typewriting machine including a revoluble platen which is laterally movable, of a sound-deadening casing including a lower body-part and a cover hinged thereto at the back, and means for rotating the platen from outside the casing, said means including a hollow platen-shaft for said platen, a splined shaft arranged for telescoping into said hollow platen-shaft and for extending therefrom through a slot in an end wall of said cover, and a finger-wheel on the outer end of said shaft, the portion of said slot below said splined shaft being positioned to extend upwardly from the lower edge of said cover on a circular arc centered on a line through the point where said cover is hinged to said body-part. 100

3. The combination with a typewriting machine including a revoluble and laterally-movable platen and mechanism for shifting said platen vertically, of a sound-deadening casing including a lower body-part and a cover hinged thereto at the back, and means for rotating the platen from outside the casing, said means including a hollow shaft for said platen, a splined shaft arranged to telescope into said hollow platen-shaft and to extend therefrom through a curved slot in 115 120 125 130

the right end wall of said cover, a finger-wheel on the outer end of said splined shaft, a bracket mounted on said platen-shifting mechanism and arranged for supporting said 5 splined shaft adjacent the inside surface of the right end wall of said cover, and a grooved plate mounted on said lower body-part adjacent said slot, said splined shaft being arranged to pass through the groove 10 in said plate and be guided thereby in line with said platen-shaft upon actuation of said platen-shifting mechanism.

4. The combination with a typewriting machine including a revoluble shiftable 15 platen operatively mounted on a slideable carriage, of a sound-deadening casing effective to deaden the noise arising from the operation of the machine, means for rotating the platen from the outside of the casing, 20 said means including a finger-wheel operatively mounted on a collapsible shaft extending from the platen-axle, and means for supporting the platen-shaft substantially in line with the platen-axis when the platen is 25 shifted to upper-case position, said last-mentioned means comprising a bracket operatively connected to the platen-shift mechanism of the machine, said bracket being effective to raise the end of the shaft to the 30 position of the platen after being shifted.

5. In a typewriting machine having a carriage arranged for letter-space travel, a platen revolubly mounted on said carriage, a hollow platen-axle, and means for shifting 35 the platen to upper or lower case type position, the combination with a sound-deadening casing comprising a body-part and a cover therefore, of a shaft telescoping into said hollow platen-axle, a finger-wheel fast 40 to the outer end of said shaft which projects through the wall of said cover, said wheel being effective to rotate the platen, and means controlled by the platen-shifting 45 means for holding the shaft in substantial alignment with the platen when the same is shifted to upper-case position.

6. In a typewriting machine having a carriage arranged for letter-space travel, a platen revolubly mounted on said carriage, 50 and means for shifting the platen to upper or lower case type position, the combination with a sound-deadening casing comprising a body-part and a cover therefor, of a collapsible shaft telescoping into a hollow platen- 55 axle, a finger-wheel fast to said shaft projecting through the wall of said casing, and said wheel being effective to rotate the platen, and means controlled by the platen-shifting 60 means for holding the shaft in substantial alignment with the platen when the same is shifted to upper-case position, said holding means including a bracket fast to a movable member of the platen-shifting 65 means, said bracket being provided with a roller revolubly mounted thereon, and said

roller co-operating with a cam face under an arm rockably mounted on a supporting bracket forming an integral part of the body-part.

7. In combination, a typewriting machine 70 having a revoluble platen, a sound-deadening casing having a lower body-part and a displaceable cover therefor pivotally fastened thereon, an instrumentality extending from said platen through said cover for rotating said platen, and means for securing said platen-rotating instrumentality against displacement upon swinging said cover upwardly. 75

8. In a typewriting machine, the combination 80 with a laterally-movable platen, a hollow platen-shaft, and a mechanism for raising said platen to upper-case position, of means for rotating said platen at a distance from one end of the same, said means 85 including a splined shaft arranged to telescope into said hollow platen-shaft, a finger-wheel at the outer end of said splined shaft, and a brace mounted on said platen-raising 90 mechanism for supporting said splined shaft adjacent said finger-wheel.

9. A sound-deadening casing for a typewriting machine including a lower body-part, a cover for said body-part, and hinges pivotally connecting said cover to said body-part at the back, said cover having a slot through an end wall extending up from the lower edge thereof to a point substantially opposite the axis of said typewriting machine, a lower portion of said slot being 100 curveyed on a circular arc whose center lies on a line through the axis of said hinges. 95

10. In combination, a typewriting machine having a revoluble platen, a hollow axle therefor, a carriage and a platen-shifting 105 mechanism, a spline-control screw in said axle extending into the hollow portion thereof of a sound-deadening casing having a body-part and a cover therefor, said cover being displaceable, means for rotating the platen 110 from the outside of the casing without necessitating the displacement of the cover, said means including a splined shaft extending into said platen-axle and outwardly 115 therefrom to the exterior of the casing and having a finger-wheel fast thereto and at the outer end thereof, the spline in said shaft engaging with a screw in said axle through which the platen is rotated by the revolving 120 action of the finger-wheel, means mounted on said mechanism for supporting the end of the shaft near the finger-wheel to raise the shaft in substantial alignment with the platen-axis when the platen is shifted to upper-case position, and means for preventing the lateral displacement of the finger-wheel when letter-feeding the platen. 125

11. A typewriting machine having a revoluble platen, a carriage and a platen-shifting mechanism, in combination with a sound- 130

- deadening casing having a body-part and a cover therefor, said cover being displaceable, means for rotating the platen from the outside of the casing without necessitating the displacement of the cover, said means including a collapsible splined shaft extending to the exterior of the casing and having a finger-wheel fast thereto and at the end thereof, the spline in said shaft engaging with a screw fast to the platen through which the platen is rotated by the revolving action of the finger-wheel, means for supporting the end of the shaft near the finger-wheel to hold the shaft in substantial alignment with the platen-axis when the platen is shifted to upper-case position, and means for preventing the lateral displacement of the finger-wheel when letter-feeding the platen, said last-two mentioned means including a rigid bracket fast to a movable member of the platen-shifting mechanism, a fixed bracket fast to the body-part of the casing and forming an integral part thereof, a shaft-supporting piece rockably mounted on the fixed bracket, said piece being operated by the rigid bracket, and a collar fast to the shaft, the collar being controlled against lateral movement between the shaft-supporting piece and the fixed bracket.
- 30 12. The combination with a typewriting machine having a platen, a laterally-movable carriage, and a paper-table at the rear of the platen, of a sound-deadening casing, and a stiff pocket fastened to said paper-table and extending rearwardly therefrom and terminating clear of the rear wall of said casing, said pocket having a flared throat adjacent said paper-table for receiving the end of a work-piece and for holding the same to prevent it from dragging against the inner surface of said casing upon lateral movement of said carriage.
- 35 13. In a typewriting machine having a revoluble platen and a carriage therefor, the carriage being arranged for letter-space travel, the combination with a sound-deadening casing having a body-part and a cover
- 40
- 45

therefor, of means for controlling the position of the trailing or bottom edge of a stiff work-sheet to prevent its engagement with the inner sides of the walls of said casing, said means including a plate at the rear of the carriage, said plate having a pocket for receiving the trailing edge of the work-sheet.

55 14. A sound-deadening casing for a type-writing machine including a lower body-part, a cover for said body-part, and hinges for pivotally connecting said cover to said body-part, said cover having a slot through an end wall extending upwardly from the lower edge thereof to a point a short distance above the intersection of said end wall and the extension of the axis of said platen when the latter is in upper-case position, a short upper portion of said slot being substantially vertical and the remainder of said slot being curved on a circular arc whose center lies on a line extending through the axis of said hinges, and a plate fastened on an end wall of said body-part and extending upwardly therefrom to be disposed closely against the slot in the end wall of the cover, so as to seal the curved portion of said slot against the emission of sound.

75 15. In a typewriting machine having a platen revolvably mounted on a shiftable platen-frame borne by a carriage arranged for letter-space travel, the combination with a sound-deadening casing having a body-part and a cover therefor, of means borne by the platen-frame for controlling the position of the trailing edge of a work-sheet around the platen to hold the edge of the work-sheet away from the walls of said casing, so as to permit the free movement of the carriage, said means including a plate fast to the platen-frame and extending substantially the full width of the platen, the plate being bent at the rear of the platen and forming a pocket for housing the trailing edge of the work-sheet.
